UNITED STATES PATENT OFFICE.

WILLIAM H. PHILLIPS, OF CHICAGO, ILLINOIS.

AUTOMATIC COAL-SPOUT-SWINGING DEVICE.

Application filed April 25, 1925. Serial No. 25,728.

My invention relates to an automatically operated coal spout swinging device.

The improvement herein described pertains to a simplified form of device for automatically feeding and distributing coal into a hopper of an automatic stoker, so that all the parts of the stoker will be amply supplied with coal; the primary aim being to improve upon and simplify the construction at present employed.

One of the main objects of my invention is to provide a simple and practical device of this type. Not only has the device been reduced to extreme simplicity, but a very efficient operation is obtained which eliminates all periods of lag occurring in the movement of the spout, thereby providing a uniform movement of the spout from end to end in the hopper as well as assuring a uniform distribution of coal, and further, overcoming the possibility of the stoker emptying the hopper at points during a time when the spout is at an unnecessary period of rest to permit the device to reverse its movement.

A further object is the provision of a device that may be embodied in a single unitary casing and attached as a unit to the front of the boiler. With this pronounced improvement, the device may be of the simplest known design and can be manufactured at a minimum cost and installed with a minimum amount of labor.

In order that no time will be wasted in feeding coal to the hopper when it is desirable to disconnect the device and manually swing the spout, a novel form of detachable connection is provided between the device and the spout.

Other objects and advantages will be apparent from the following description when read in connection with the accompanying drawings, in which:

In the drawings:

Figure 1 is a front elevation of the lower portion of a boiler having an automatic coal spout swinging device embodying my invention; this view showing the device applied to a boiler having more than one coal spout and illustrating the manner of providing the device in units to operate more than one spout;

Fig. 2 is a detailed sectional view taken on line 2—2 of Fig. 1, illustrating the interconnecting drive between units;

Fig. 3 is an enlarged elevational view of a device in the form of a single unit;

Fig. 4 is a transverse sectional view taken on line 4—4 of Fig. 3;

Fig. 5 is a similar view taken on line 5—5 of Fig. 3;

Fig. 6 is also a similar view, but taken on line 6—6 of Fig. 3.

Referring to the drawings, the spouts 2 may be connected to an upper floor in the customary manner so as to feed the coal by gravity from suitable bins and to be free to swing in a vertical plane back and forth across the front of the boiler 3, and also to be capable of being withdrawn from hoppers 4 and swung outwardly, for permitting the operator to obtain a charge of fuel which he may desire to use elsewhere. Handles 5 are attached to the lower end of the spout for permitting manual operation if it should become necessary.

It is quite customary at the present time to employ a large number of such boilers in a single power station. Usually all of these boilers are not continuously operated, but are provided to take care of peak loads occurring during certain periods of the day. It will be observed, therefore, that if the spouts 2 are swung back and forth along the hoppers 4 by men, a correspondingly large amount of labor would be required only during the hours of these peak loads. By employing my invention, it is possible to eliminate this labor required during only a limited part of the day. A single man may operate a larger number of boilers when the spouts are mechanically swung by means of the automatic swinging mechanism disclosed herein.

This mechanism comprises preferably a unitary frame 7 that may be made in different lengths and quickly attached as a unit to the front of the boiler. By providing the mechanism as an appliance capable of being attached to the front of the boiler as a unit and requiring a minimum number of connections, I find that the field for the use of the mechanism is considerably increased and that power plant operators are more inclined to adopt mechanical coal spout swinging devices because of the minimum expense involved in the original installation as well as in the maintenance thereof.

The mechanism is mounted upon a frame 7, comprising an upper and lower track 8

and 9 respectively, which are spaced apart by sprocket carrying plates 10. Tracks 8 and 9 preferably consist of opposed inverted V irons, each having an inwardly extending lateral flange 19 between which the sprocket blocks 10 are bolted as indicated at 11 in Figs. 4 and 6. Stub shafts 12 and 13 are suitably journaled in these sprocket blocks 10. Shaft 13 extends a suitable distance behind the frame for carrying thereon a beveled gear 37, which is adapted to mesh with a second beveled gear 38. Beveled gear 38 is preferably carried on a cross shaft 16, to which is connected a sprocket 17, driven by means of a chain 18. This chain may extend from the drive of the automatic stoker, if so desired, or it may extend from any other suitable source of power. Sprockets 14 and 15 are carried on the outer or opposite ends of the shafts 12 and 13. It will be noted in Figs. 4 and 6 that this arrangement permits these sprockets to lie, in compact relation, within the plane of the tracks 8 and 9.

25 And endless belt or chain 18 is carried by the two sprockets 14 and 15 and is adapted, in this particular instance, due to the driving connection leading to the automatic stoker, to continuously rotate about these sprockets for reciprocating the element engaging and moving the chute 2 back and forth across the hopper 4, which element will be presently described. I find that the V-shaped tracks serve, to a certain extent, to protect 35 the chain 18, having the aspect of a housing for the chain, due to the positioning of the chain in the plane of these tracks.

The element connecting to the spout comprises a shuttle 20, designed in the form of a plate having lugs 21 extending from the four corners thereof. These lugs function as bearings for shafts 22 carrying a plurality of upper and lower pulleys 23 and 24. These pulleys are provided with V-shaped 45 grooves for riding over the V portion of the tracks 8 and 9. Suitable thrust bearings 25 may be provided for the pulleys 23 and 24, it being here noted that the V formation of the pulleys and the tracks tend 50 to prevent lateral shifting of the shuttle 20 in its movement back and forth across the front of the furnace 3. At any point on the chain, a pin 26 may be fastened to ride in a vertical slot 27 formed in the shuttle 20. This pin 26 is carried along on the chain and 55 travels about the end sprockets 14 and 15, remaining either at the upper or lower end of the slot 27 when traveling along the upper or lower runs of chain 18, and moving 60 vertically in a slot 27 when traveling about either of these end sprockets 14 and 15. This arrangement is extremely simple and 65 substantially eliminates any period of lag in the movement of the shuttle, due to the pin 26 changing from the upper to the lower

runs of chain 18. Consequently, the coal is distributed or fed evenly as a result of a uniform travel of the spout 2 at a certain speed back and forth in the hopper 4. Moreover, it will be noted that this arrangement further permits this spout to travel the entire length of the hopper, which is a decided advantage in this type of device.

70 Lugs 30 are formed on the outer face of the shuttle 20 for receiving in pivotal relation a yoke 31. This yoke is substantially semi-circular in formation for embracing in forked relation the spout 2. When it is desirable to free the spout the operator needs 75 but throw the yoke 31 backwardly on its pivotal fastening and then manipulate the spout by the handle 5.

In operation, the chain 18 is driven in the direction of the arrows, as shown, whenever the device is in operation. As the chain 18 85 moves, the pin 26 travels first to the right along the upper run of this chain, then around the sprocket 14, then to the left along the lower run of the chain and then around the sprocket 15 back to said upper 90 run. In this movement, the pin 26 acts through the slot 27 to move the shuttle plate 20 back and forth along the hopper 4. When the pin 26 moves around the end sprocket 14, it gradually moves downwardly through 95 the slot 27, causing the plate 20 to have practically no period of rest at this end of its movement. Likewise, the pin will start upwardly in the slot 27 when it travels around the opposite end sprocket 15 until it reaches 100 the upper end of this slot, whence it then continues forwardly along the upper run of the chain. During this time, the spout which is connected to the shuttle is being swung 105 back and forth across the hopper 4 to evenly distribute coal therein. The movement of the spout is practically uniform between the ends of the hopper.

The swinging mechanism shown herein 110 may be provided in any number of units across the front of a single boiler. The number of units so provided depends upon the number of spouts used to feed coal to any particular boiler. In Fig. 1, there is shown a boiler having a pair of spouts, and 115 there is also shown a swinging mechanism embodying my invention in the form of two units, both of which operate in a single frame. The drive from one chain to the other is through a driving connection comprising a chain 32 trained around a pair of sprockets 33 and 34 carried at the inner ends 120 of the shafts 35. Where it is preferable to install this type of swinging mechanism, I find it of practical advantage to arrange 125 the tracks 8 and 9 of both units co-extensive or integral, as shown, so that both units may be carried by a single frame. This minimizes the labor required to install the mechanism, and furthermore permits these units 130

to be provided in the form of a single unitary installation. It will be observed at this point in the description that the spouts of each unit may be so arranged with respect 5 to the other as to obtain a balance drive. That is to say, one spout may be moving away from the center in an upward movement through the arc defining its path of travel, while the other spout may be moving 10 downwardly towards the center on its opposite side. When moving downwardly, this other spout will, of course, be assisted by gravity and will thereby tend to impart energy to its chain 18. This imparted energy 15 is then utilized through the interconnecting chain 32 to overcome the added resistance which the first spout offers to its chain 18 as a result of it moving upwardly against gravity. Any number of spouts may be 20 arranged and driven from one source of drive, such as has been illustrated at 18 and consequently I do not intend to be limited to the disclosure illustrated in Figure 1.

In so far as the common subject matter is 25 concerned, the present invention is a continuation of my copending application Serial Number 755,466 and filed December 12, 1924.

I claim:

1. In mechanism for use with an automatic stoker provided with a hopper and a hopper feeding chute arranged to feed coal into said hopper and to swing back and forth to distribute coal along the hopper, a member movable back and forth along said hopper, and a shuttle connected to said chute, said shuttle being provided with a slot which engages said member, said member riding in said slot and causing said shuttle to swing said chute continuously back and forth the 40 length of the travel of said member.

2. In mechanism for use with an automatic stoker provided with a hopper and a hopper feeding chute arranged to feed coal into said hopper and to swing back and forth 45 to distribute coal along the hopper, a member movable back and forth along said hopper, and a shuttle connected to said chute, said shuttle being provided with a vertical slot which engages said member, said member riding in said slot and carrying said shuttle back and forth along said hopper the length of the travel of said member.

3. In mechanism for use with an automatic stoker provided with a hopper and a hopper feeding chute arranged to feed coal into said hopper and to swing back and forth to distribute coal along the hopper, a member movable back and forth along said hopper, and a reciprocating device serving to 60 interconnect said chute and said member, said reciprocating device being mounted to provide continuous movement to said chute and to swing said chute substantially the entire travel of said member.

4. In combination with an automatic

stoker, and a hopper therefor, a swinging chute arranged to move back and forth to distribute coal along said hopper, a member movable back and forth along said hopper, a reciprocating device, a track, means for 70 guiding said device along said track, and means providing a connection between said member and said reciprocating device, said chute being connected to said reciprocating device.

5. In combination with an automatic stoker, and a hopper therefor, a swinging chute arranged to move back and forth to distribute coal along said hopper, an endless belt, means for driving said belt, and 80 means providing a continuous movement to said chute comprising a reciprocating device connected to said chute and provided with a slot therein, and a pin projecting from said endless belt and engaging in said 85 slot for moving said device back and forth across said hopper the length of the travel of said pin.

6. In combination with an automatic stoker, and a hopper therefor, a swinging chute arranged to move back and forth to distribute coal along said hopper, an endless belt extending parallel to the swinging of said swinging chute, a track and a shuttle movable upon said track adjacent to said belt, and a driving connection extending from said belt for engagement with said shuttle, said chute being connected to said shuttle.

7. In combination with an automatic stoker, a hopper therefor and a swinging chute arranged to move back and forth to distribute coal along said hopper, of a mechanically operated chute swinging device comprising an endless belt extending substantially parallel to the swinging of said swinging chute, a shuttle, a trackway, rollers for supporting said shuttle in a manner on said trackway preventing lateral displacement of said shuttle, and means for connecting said shuttle to a point on said belt and also to a point on said swinging chute.

8. In combination with an automatic stoker, a hopper therefor and a swinging chute arranged to move back and forth to distribute coal along said hopper, of a mechanically operated chute swinging device comprising a continuously driven chain, a trackway upon which a shuttle is adapted to travel in a reciprocating motion, said shuttle being disposed between said swinging chute and said chain, and means for interconnecting said shuttle with said chute and with a continuously travelling point driven by said chain.

9. In combination with a stoker and a plurality of swinging chutes arranged to move back and forth to distribute coal along hoppers provided therefor, of a plurality of automatic swinging devices for said chutes,

said devices comprising a plurality of endless chains, reciprocating shuttle-like members driven by said chains and connected to said chutes, and means for interconnecting 5 said chains so as to operate from a common drive, said chutes being connected to said chains at points permitting said chutes to balance each other in their movements back and forth along said hopper.

10 10. In combination with a stoker and a plurality of swinging chutes arranged to

move back and forth to distribute coal along hoppers provided therefor, of a plurality of endless chains, means for operably connecting said chains together, means for driving 15 said chains, and a shuttle for each chain connected to said chutes at points along said chains to permit a balanced movement of said chutes.

In witness whereof, I have hereunto sub- 20 scribed my name.

WILLIAM H. PHILLIPS.
